(57) **CLAIM**

The ornamental design for a strap for rangefinder, as shown and described.

DESCRIPTION

FIG. 1 is a front, top, right-side perspective view of a strap for rangefinder showing my new design;

FIG. 2 is a rear, bottom, right-side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view thereof showing a configuration of use.

The broken lines in drawing FIGS. 1-8 show portions of the strap for rangefinder that form no part of the claimed design. The broken lines in drawing FIG. 9 adjacent to the article show environmental structure that form no part of the claimed design.
